US00D836872S

(12) **United States Design Patent** (10) **Patent No.:** **US D836,872 S**
(45) **Date of Patent:** **** Dec. 25, 2018**

(54) **MOP BODY**

(71) Applicant: **SharkNinja Operating LLC**, Newton, MA (US)

(72) Inventors: **Scott Benjamin Niedzwecki**, Walpole, MA (US); **Junghwan Chei**, Chestnut Hill, MA (US)

(73) Assignee: **SharkNinja Operating LLC**, Needham, MA (US)

(**) Term: **15 Years**

(21) Appl. No.: **29/566,108**

(22) Filed: **May 26, 2016**

(51) LOC (11) Cl. **07-05**

(52) U.S. Cl.

USPC **D32/50**

(58) **Field of Classification Search**

USPC D32/40-45, 49-52, 21-25; D4/116, 118, D4/137; D8/107, 10-11
